UNITED STATES PATENT OFFICE.

GEORGE W. KNIGHT, OF HOPEDALE, MASSACHUSETTS, ASSIGNOR TO DRAPER COMPANY, OF HOPEDALE, MASSACHUSETTS, A CORPORATION OF MAINE.

BOBBIN-CLUTCHING MEANS FOR ROTATABLLE SPINDLES.

No. 923,126.

Specification of Letters Patent.

Patented May 25, 1909.

Application filed January 18, 1909. Serial No. 472,999.

To all whom it may concern:

Be it known that I, GEORGE W. KNIGHT, a citizen of the United States, and resident of Hopedale, county of Worcester, State of Massachusetts, have invented an Improvement in Bobbin-Clutching Means for Rotatable Spindles, of which the following description, in connection with the accompanying drawing, is a specification, like characters on the drawing representing like parts.

This invention relates to bobbin-clutching means of the type wherein the clutching members are arranged symmetrically about the spinning or other rotatable spindle and by the action of centrifugal force engage and hold the bobbin securely in place upon the spindle to be rotated therewith.

In my present invention the clutching members are bodily movable outwardly from the spindle when the latter is running at speed, and I have also made provision for a tipping or rocking movement of such members on their lower ends, means being provided to effect such rocking movement positively and equally for all of the clutching members when the bobbin is applied to the spindle.

The object of this construction and arrangement is to properly center the bobbin on the spindle, for sometimes the centrifugal action upon the clutching members is not sufficient to effect the requisite centering, particularly with unbalanced loads, and at such times the operation of the device is not so efficient as it should be.

In the present embodiment of my invention the lower ends of the clutching members are shaped to present outturned feet, upon which the members rock, and I find that the added weight thus provided at the lower ends of the members is also advantageous in improving the clutching action upon the bobbin. The feet are loosely inserted in a covered guard or container, and by means of projections on the feet, projecting upward through the top of the container, the head of the bobbin acts to tip or rock the clutching members, moving their upper ends outward positively and equally to thereby effect the centering of the bobbin.

The various novel features of my invention will be fully described in the subjoined specification and particularly pointed out in the following claims.

Figure 1 is a side elevation of a rotatable

spindle having bobbin-clutching means embodying my present invention, the lower or head end of a bobbin being shown in section in operative position on the spindle. Fig. 2 is a part elevation and vertical diametrical section on the line 2—2, Fig. 1, to more clearly show the structure. Fig. 3 is a horizontal section on the line 3—3, Fig. 2, looking down, the bobbin being omitted and the cover or top of the container being partly broken out. Fig. 4 is a similar view but with the clutching members and the cover of the guard or container removed. Fig. 5 is a perspective view of one of the clutching members, detached.

As herein shown my invention is applied to a rotatable spindle A having an attached whirl B provided with an upturned sleeve B' connecting it with the spindle, the head B² of the whirl being enlarged and provided with an upturned annular flange or wall B³, to form a cup-like container or guard for the lower ends of the clutching members, as will appear hereinafter.

As shown in Figs. 2 and 4 the bottom of the container is provided with symmetrically arranged recesses or sockets 1, three being shown, and preferably elongated in radial lines from the center of the spindle. The container is covered or inclosed by a cap or cover 2 which slips on outside the wall B³ and is held in place thereon by a pin 3, Fig. 2, the cover having a central circular opening 4 of sufficient diameter to receive loosely, the bodies of the clutching members and permit bodily radial movement thereof as well as a rocking movement.

A clutching member is shown separately in Fig. 5 and comprises an elongated body 5 segmental in cross-section and longitudinally convexed or curved at its upper end or head 6, on the interior of which is an upturned projection 7 which is engaged by the depending flange 8 of a collar 9 fast on the spindle, as shown in Fig. 2, the coöperation of the flange 8 with the projections 7 of the several clutching members limiting outward movement thereof at their upper ends.

Three of the clutching members are herein shown arranged symmetrically around the spindle A and surrounding the sleeve B', each member having at its lower end an outturned, segmental foot 10 the under face or bottom of each foot being beveled or inclined upwardly and outwardly from its

inner edge, as at 11. As shown in Fig. 2 the clutching members are vertically supported by the inner edges of the feet, which rest on the bottom of the container or guard, and the beveling of the feet permits the members to rock or tip on such inner edges of the feet, as will be apparent, while the members as a whole have a limited outward bodily movement with relation to the spindle. When the spindle is running free the centrifugal force throws the clutching members outward, the movement at their heads being limited by the flange 9 and projections 7, and the lower ends of said members are limited in such movement by the edge of the circular opening 4 in the cover 2, the feet being inclosed within the container by such cover.

In order to maintain the clutching members properly separated from each other and to effect their rotation by and with the spindle I provide pins 12, driven through the feet 10, the lower ends of the pins loosely entering the sockets 1, see Fig. 2, while their upper ends pass through preferably radial slots 13 in the cover 2, and when the spindle is bare the upper ends project above the upper surface of the cover, in position to be engaged by the head C' of the bobbin C, Figs. 1 and 2, when applied to the spindle. When the bobbin is applied it is pushed down over the clutching members and its end strikes the projecting ends of the pins 12 and presses the latter downward, rocking the clutching members equally and simultaneously and causing their heads 6 to press uniformly against the wall of the chamber C^x, thereby centering the bobbin with respect to the spindle. The pins are preferably of such length that their upper ends will lie flush with the top of the cover 2, see Fig. 2, when the bobbin is pushed down onto said cover, which latter then serves as a bobbin rest.

By reference to Fig. 2 it will be seen that a slight clearance is left between the bottom of the socket 1 and the lower end of the pin 12 when the clutching members are rocked, to prevent any hindrance to the rocking movement, and also leaving the clutching members free to move outward bodily under the influence of centrifugal action.

In actual practice I find that the operation of the device herein described is very efficient, inasmuch as the bobbin-centering feature, which is of great value, does not interfere with the centrifugally-controlled clutching action of the loose members upon the bobbin, so that the latter is positively and accurately centered and at the same time held in proper position to rotate by and with the bobbin by centrifugal action. The container not only protects and incloses the feet of the clutching members, preventing any possibility of injury to the hands of the

attendant, but it also serves as a housing to loosely receive the feet, and prevents the entrance of lint or fluff.

Having fully described my invention, what I claim as new and desire to secure by Letters Patent is:—

1. The combination, with a rotatable spindle, of a plurality of centrifugally-acting bobbin-clutching members mounted upon it and bodily rotatable therewith, each member having at its lower end an outturned foot upon which the member is adapted to rock, an inclosing container in which the feet are supported and adapted to rock and move radially, means coöperating with the clutching members near their upper ends to limit outward movement thereof, and means to rock said members upon their feet and force their upper ends outward when a bobbin is applied to the spindle, to center the bobbin thereupon.

2. The combination, with a rotatable spindle, of a plurality of centrifugally-acting bobbin-clutching members mounted upon it and bodily rotatable therewith, each member being adapted to rock upon its lower end, means coöperating with the inner portions of said members at their upper ends to limit outward movement thereof, an inclosed support for the lower ends of the clutching members, and means to rock said members positively and force their upper ends outward by the application of a bobbin to the spindle.

3. The combination, with a rotatable spindle, of a plurality of centrifugally-acting bobbin-clutching members mounted thereon and adapted to rock upon their lower ends and also to move bodily in radial directions, and upturned means on the lower ends of said members to engage the end of the bobbin when applied to the spindle and effect thereby by rocking movement of the clutching members, to cause the same to act equally and uniformly upon the bobbin and center it with relation to the spindle.

4. The combination, with a rotatable spindle, of a plurality of centrifugally-acting bobbin-clutching members mounted thereon and bodily movable in radial directions, each member having an outturned foot outwardly and upwardly beveled on its under face, an inclosing container or guard in which the feet are movable radially and also can rock, and upturned projections on the feet adapted to be engaged and depressed by the bobbin when applied to the spindle, to thereby rock the clutching members and press their upper ends outward to internally engage and center the bobbin.

5. The combination, with a rotatable spindle, of a plurality of centrifugally-acting bobbin-clutching members mounted thereon and bodily movable in radial directions, each member having an outturned foot upon the inner edge of which the member rocks, a con-

tainer loosely inclosing the feet and having radial sockets in its bottom and corresponding openings in its top, and pins on the feet projecting into the sockets to separate the clutching members and passing up through the openings in the top of the container, to be engaged by the end of a bobbin when applied to the spindle and serving to rock the clutching members equally and positively.

10 6. The combination, with a rotatable spindle, of a plurality of centrifugally-acting bobbin-clutching members mounted thereon and each having an outturned foot on its lower end, a cup-like container loosely inclosing the

feet and fixedly mounted on the spindle, depending projections on the feet to enter sockets formed in the bottom of the container, to separate the clutching members, and means coöperating with the inner faces of said members near their upper ends to limit outward movement thereof.

In testimony whereof, I have signed my name to this specification, in the presence of two subscribing witnesses.

GEORGE W. KNIGHT.
